CLAIM

We claim the ornamental design for lift top cocktail table, as shown and described.

DESCRIPTION

FIG. 1 is a perspective view of a lift top cocktail table of the invention.

FIG. 2 is a front elevational view of a lift top cocktail table of the invention. The view from the opposite side is identical thereto.

FIG. 3 is a perspective view of a lift top cocktail table of the invention where the table top elevated; and,

FIG. 4 is a side elevational view of a lift top cocktail table of the invention. The view from the opposite side is identical thereto.

The broken lines showing in the lift top cocktail table are for the purpose of illustrating portions of the lift top cocktail table and form no part of the claimed design.
